W. C. IFTIGER,
QUICKLY REMOVABLE DUST CAP,
FILED JAN. 11, 1921.

FIG. 1.

UNITED STATES PATENT OFFICE.

WILLIAM CARL IFTIGER, OF LOS ANGELES, CALIFORNIA.

QUICKLY-REMOVABLE DUST CAP.

Application filed January 11, 1921. Serial No. 436,555.

To all whom it may concern:

Be it known that I, WILLIAM C. IFTIGER, a citizen of the United States, residing at Los Angeles, in the county of Los Angeles and State of California, have invented new and useful Improvements in Quickly-Removable Dust Caps, of which the following is a specification.

It is the object of this invention to provide a cap for nipples and the like, which will be readily removable and as readily inserted in position over a nipple. The device is particularly adapted to be employed as the dust cap for a usual valve stem of a pneumatic tire.

The invention will be readily understood from the following description of the accompanying drawings, in which:

Figure 1 is a side elevation of a cap constructed in accordance with the invention.

Fig. 2 is an enlarged vertical section through the same mounted upon a nipple.

Fig. 3 is a side elevation of the nipple upon which the cap is mounted.

Fig. 4 is a transverse section on the line 4—4 of Fig. 2.

Fig. 5 is a longitudinal section through the valve stem of a tire having a dust cap constructed in accordance with the invention, mounted thereon.

Fig. 6 is a transverse section on the line 6—6 of Fig. 5.

In the form of the invention illustrated in Figs. 1 to 4, I have shown the improved cap as arranged to be received upon a nipple 1, having the base flange 2 terminating in the threaded projection 3 by means of which the nipple is mounted in position.

The improved cap comprises a cylindrical member 4 having the enlarged end plate 5 for closing one end of the same, and preferably formed of such size and material as to maintain its shape at all times. The open end of the cap is provided with an enlarged annular flange 6, which is also of such size and material as to maintain a concentric annular shape. The cap as thus constructed, is adapted to be slipped over nipple 1, and a packing 7 of cork or the like, is preferably provided within the head of the cap, so as to be received against the end of the nipple, in order to provide a tight joint.

The material forming the body 4 of the cap is, preferably, of somewhat resilient metal, and opposite sides of said body portion of the cap are provided with elongated flattened portions 8, which in transverse section are closer to one another than the concentric portions of the circumference of the cap, as clearly shown in Fig. 4. The cap is arranged to fit relatively snugly over nipple 1, and as a consequence, the flattened portions 8 of the cap will frictionally bear against the nipple for retaining the cap in position when placed over the nipple. The frictional engagement thus provided will hold the cap against displacement under ordinary circumstances, but at the same time the cap may be readily removed by pulling upon the same with sufficient force.

In the form of the invention illustrated in Figs. 5 and 6, I have shown a usual valve stem 1^a for a pneumatic tire having the usual longitudinally extending flattened sides 10 and usual threads 11 provided upon the stem. The dust cap for this stem is constructed similar to the cap previously described, including the main cap portion 4^a, end plate 5^a and base flange 6^a. The sides of the cap are flattened longitudinally of the same, as shown at 8^a, so that said flattened sides will be received against the flattened surfaces 10 of the valve stem when the dust cap is placed upon the valve stem for frictionally holding the cap to the stem.

It will thus be seen that I have provided an extremely simple means for retaining a cap upon a nipple or the like, by simply flattening opposite sides of the cap sufficiently to cause frictional engagement between the cap and nipple. The cap is thus held in position against displacement under normal conditions, but may be quickly withdrawn from the nipple by pulling upon the same.

Various changes may be made without departing from the spirit of the invention as claimed.

What is claimed is:—

1. The combination with a concentric nipple of a cap formed of resilient metal received over the same and having flattened sides intermediate its ends for frictional engagement with said nipple.

2. A cap comprising a cylindrical body portion having flattened opposite sides and formed of slightly resilient material, and a closure plate and a flange at the respective ends of said cap for stiffening the same.

3. A cap comprising a body formed of resilient metal having a restricted portion

adapted to be expanded on application of the cap to a nipple for frictionally retaining the cap upon the nipple when said cap is placed over the nipple in an axial direction.

In testimony whereof I have signed my name to this specification.

WILLIAM CARL IFTIGER.
